FIG. 1

FIG. 2

FIG. 1 is a perspective view of an umbrella showing my new design; and

FIG. 2 is an elevational view of the umbrella shown in FIG. 1.

The characteristic feature of my design resides in the combination on the open umbrella disclosed, of the deep dome of the cover and the highly disposed stretchers, whereby to impart to the umbrella a double curvature from its top closed end to its bottom open end, the extremities of the lower curved portion being significantly divergent with respect to the central axis of the umbrella.

I claim:
